UNITED STATES PATENT OFFICE.

OSKAR JUNGHANS, OF SCHRAMBERG, GERMANY; SIEGFRIED JUNGHANS, ADMINISTRATOR OF SAID OSKAR JUNGHANS, DECEASED.

SETTING MACHINE FOR TIME FUSES.

Application filed October 7, 1926, Serial No. 140,105, and in Germany January 15, 1926.

This invention relates to machines for setting mechanical time fuses which are applied to artillery projectiles for the purpose of exploding the projectile after lapse of a given time following the firing of the projectile from a gun, and more particularly to a machine comprising a setting device having two parts which are adapted to be adjusted or set with relation to each other and which are secured in their adjusted or set position by means of a releasable locking device.

The object of the invention viewed from its broadest aspect, is to provide a machine having a plurality of setting units or devices adapted to be set, locked or released simultaneously or jointly, so that the machine will afford the possibility of setting several fuses at the same time and moreover setting the same in a manner that the several fuses will be adjusted or timed for different predetermined periods which is of advantage in all cases where it is difficult to exactly value the true distance between the gun and the aim, particularly in case of defense against aeroplanes.

With the above recited object in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed, and that the phraseology which I have adopted is for the purpose of description and not of limitation except where the sense absolutely requires it.

In the accompanying drawings, forming a part of this specification and showing for purposes of exemplification a preferred form and manner in which the invention may be embodied and practiced, but without limiting the claimed invention to such illustrative instance:

Figure 1 is a longitudinal vertical section of a machine equipped with means for setting three fuses at a time or simultaneously;

Figure 2 is a vertical cross-section thereof, partly in elevation;

Figure 3 is a front view thereof;

Figure 4 is a view in top plan, partly in section;

Figure 5 is a front view of a detail forming a rotary part of the horizontally disposed setting unit, and

Figure 6 is an elevation of a lock mechanism employed in each setting unit.

Where desirable the same reference symbols are used in the different figures to denote corresponding parts.

The machine comprises a frame 1 adapted to be firmly attached to the gun-carriage or to any other suitable support, and, as hereinbefore mentioned, three setting units are provided one of which is disposed in a horizontal plane while the other two are arranged vertically with relation to the former. The horizontal setting unit or device comprises a cylindrical part 2 mounted in the frame so as to be revoluble therein, a hand-wheel 3 being rigidly connected with the said part 2 by means of screws, and provided with a scale as usual, cooperating with a stationary index or pointer 4 fixed to the frame, as will be clearly seen in Figure 4, to indicate the degree or value to which the hand-wheel has been set. Mounted in the cylindrical part or casing 2 as a cylindrical cup 5 the longitudinal axis of which coincides with the axis of the casing 2, but which is stationary that is to say, prevented from rotation in the latter, as will be explained more in detail.

In front of the parts 2 and 5 forming a setting unit or device there is provided a support 6 for the projectile equipped with the fuse to be set and it will be seen in Figure 1 that the shape and size of the cylindrical cup 5 is such as to permit introducing the fuse sufficiently, that is to the required depth, no matter whether the same is rounded or tapering, as indicated by dotted lines in Figure 1. In the front end of the rotary casing 2 there is a spring-controlled detent 7 adapted to engage in a correspondingly shaped recess of the base section of the fuse firmly attached to the projectile. The cylindrical cup 5 is likewise provided with a spring-controlled nose or detent 8 adapted to catch, under the action of its spring 9, into the top section or cap of the fuse which is adapted to be rotated for the timing purpose, see Figures 1 and 5.

The construction of the machine so far described is known from a general point of view.

Laterally adjacent to the horizontal set-

ting unit constituted mainly by the two parts 2 and 5, there are provided two similar setting units or devices constituted by similar parts 10, 11 and 12, 13, respectively, and 5 mounted in the frame so as to occupy vertical positions with relation to the described setting unit 2, 5. The casings 10 and 12, respectively, of the two vertical setting units are likewise capable of rotation, while the 10 two inner cups 11 and 13, respectively, thereof are stationary in the supporting casings, just as the corresponding parts of the horizontal setting unit, and in a similar manner spring-controlled noses or detents 7 and 8, 15 see Figure 2, adapted to engage in correspondingly-shaped recesses of the two sections of the fuses; are provided in the casings and the cups of the vertical setting devices. In the top of the latter there are also provided 20 tubular holders 6¹ and 6² for the reception of the projectiles and these holders, therefore, serve the same purpose as the support 6 the only difference being that the projectile is to be inserted vertically therein 25 with the fuse downwards.

Intermediate between its two ends the casing 2 of the setting unit 2, 5 is shaped on its outer periphery to form a kind of a worm-wheel 14 adapted to engage in corresponding 30 worm-wheels or rims 14¹ and 14² provided on the casings 10 and 12, respectively, of the two vertical setting devices, so that upon turning the hand-wheel 3 both the horizontal setting unit or device 2, 5 and the two 35 vertical setting devices 10, 11 and 12, 13 will be rotated in unison. Mounted between the parts 2 and 5, 10 and 11 and 12 and 13 of the three setting devices, respectively, is a lock mechanism consisting of friction rollers 15 supported alternately in or by annular discs 40 17 and 18, in the horizontal setting device, and annular discs 19 and 20 in the two vertical setting devices. All of these clamping or friction rollers are controlled by springs 45 39 each mounted between two adjacent rollers and acting to hold the rollers in frictional engagement. The rollers 15 lie in recesses of the stationary parts 5, 11 and 13 of the setting devices and are adapted to normally 50 prevent the rotatable parts or casings 2, 10 and 12 thereof from rotation in a manner which is known in itself. The said recesses in which the rollers 15 are accommodated, 55 are of increasing width towards the one end thereof. By turning the annular discs with relation to each other the lock mechanisms may be released or unlocked for the purpose of adjusting the machine, when required or desired.

60 To this end a handle 21 keyed to a shaft 22 is provided at the front end of the machine. The shaft 22 is supported in suitable bearings in the bottom of the frame 1 and immediately behind the front bearing 65 a pinion 23 is keyed to the shaft meshing

with a spur gear wheel 24 of a train of toothed wheels 24, 25 and 26. The actuating shaft 27 of the wheel 26 thus will be turned, upon the rotation of the shaft 22 by means of the handle 21, and as the flat shaped inner end 28 of the shaft 27 engages 70 between the annular discs or rings 17 and 18, see Figures 1 and 6, the latter will be displaced from the released position to the locked position, or vice versa, just as the 75 handle 21 is turned in the one or the other direction.

Keyed to the rear end of the shaft 22 is a worm-wheel 29 meshing with a similar wheel 30 keyed to a transverse shaft 31 duly supported in bearings provided on the bottom 80 of the frame. Firmly connected to the extremities of the shaft 31 are two cams 32 each adapted to co-operate with two rollers 85 of two levers 33 and 34 for the purpose of turning or swinging the same at the same time in opposite directions and against the action of springs controlling the said levers. Each pair of levers 33 and 34 engage between the annular discs or rings 19 and 20 90 of the friction roller lock mechanisms of the two vertical setting devices, respectively, the arrangement being such that upon turning the handle 21 for 90 degrees in the one or the other direction the friction roller mechanisms will be simultaneously caused to lock 95 the casings and prevent them from rotation or to unlock the same and allow them to rotate.

The inner cylindrical cup 5 of the horizontal setting device is elongated at its front end to form a shaft-like extension on which a disc 35 is loosely mounted so as to be movable lengthwise on the shaft-like extension, but prevented from rotation thereabout by 100 means of a guiding rod 36 mounted in a suitable guiding bracket in parallelism to the said shaft or extension. The front or free end of the latter is bored and threaded for the reception of a screw 37 secured 105 against displacement in axial direction and having on its free end a handle 38. By turning the handle 38 which is rigidly connected with the screw 37, the setting device comprising the parts 2 and 5, the hand-wheel 110 3 and the scale attached to the latter can be moved as a unit in the direction of the axis 115 of the parts.

The operation of the machine is as follows:

120 By manually turning the handle 21 in the required direction the friction roller mechanism of the three setting devices are released or unlocked and then, by turning manually the hand-wheel 3 all of the three 125 setting devices are set to the desired period. This done the handle 21 is turned in opposite direction in order to return the friction roller mechanism to their locking positions whereby the rotatable parts or casings 2, 10 130

and 12 of the several setting devices are simultaneously locked and secured against rotation. The machine now is ready for use, that is for the reception of the projectiles 5 with the fuses duly attached thereto. The projectiles are inserted into the supports or holders 6, 6¹ and 6² respectively, in a manner that the detents 8 engage in the correspondingly shaped recesses provided for the purpose in the top sections of the fuses, as hereinbefore explained, whereupon the projectiles are to be turned about their axes until the detents 7 catch into the recesses provided for the purpose in the base sections of the 15 fuses which are firmly connected with the projectiles.

In some cases it will be desirable to set the three fuses for different periods or desired times of ignition, that is to say, for 20 instance, to set and time the fuse in the horizontal setting device exactly to the calculated or desired period, the second fuse to a period a little in excess thereof and the third fuse a little below the calculated or 25 desired period. In the described machine it is only necessary for the purpose to turn, previously to the operation of returning the friction roller mechanisms to the locking position, the screw 37 by means of the handle 30 38 in order to displace the cylindrical cup 5 of the horizontal setting device a little in axial direction. As above described the casting 2 of the horizontal setting device is also displaced simultaneously therewith and the 35 axial displacement of the latter results in that, due to the particular construction and arrangement of the worm-wheel gearings 14, 14¹ and 14², the two vertical setting devices are displaced for a certain small 40 amount, with relation to the period of the horizontal setting device, that is to say, the one to the right hand side, the other one to the left hand side or the one in clockwise direction and the other one in anti- 45 clockwise direction, so that the periods which the two vertical setting devices will set, will differ a little from the period of the horizontal setting device, upwards and downwards, respectively. Consequently the 50 fuses of the three projectiles to be set by the machine will actually be set for different periods as desired.

What I claim is:—

1. A setting machine for timing or setting fuses in projectiles comprising a horizontal 55 setting device; two vertical setting devices, said devices comprising a stationary part and a rotatable part; gearing for interconnecting the rotatable parts of the devices; and a single handle for simultaneously setting said rotatable parts.

2. A setting machine for timing or setting fuses in projectiles comprising a horizontal setting device; two vertical setting devices, said devices comprising a stationary 65 part and a rotatable part; gearing for interconnecting the rotatable parts of the devices; a single handle for simultaneously setting said rotatable parts; and a friction roller mechanism for locking the rotatable parts, said mechanism comprising rollers, annular discs in which the rollers are alternately mounted, and adapted to be displaced with relation to each other, a shaft simultaneously operating the discs and for 70 throwing the rollers out upon rotation of said discs, a train of toothed wheels and an actuating shaft for operating the discs of the horizontal setting device, and a plurality of levers for operating the discs of the vertical setting devices. 75 80

3. A setting machine for timing or setting fuses in projectiles according to claim 2 in which a stationary part of the horizontal setting device is displaceable in axial direction, so that upon displacement of the stationary part, one of said vertical setting devices will be set or timed to be a little in advance of the period of the horizontal setting device and the other vertical setting 85 90 device will be set or timed for a little shorter period than that of the horizontal setting device.

4. A setting machine for timing or setting fuses in projectiles comprising a plurality 95 of setting devices for the reception of a plurality of projectiles each comprising a stationary part and a rotatable part adapted to be adjusted with relation to each other; gearing for interconnecting the rotatable parts; a single handle for simultaneously setting said rotatable parts; and a friction roller mechanism for locking the rotatable parts. 100

In testimony whereof I affix my signature.
OSKAR JUNGHANS.
